SHOE SEWING MACHINE

Edward Quinn, Malden, and Leonard S. Curtin,
Belmont, Mass., assignors to United Shoe Ma-
chinery Corporation, Flemington, N. J., a cor-
poration of New Jersey

Application March 7, 1941, Serial No. 382,184

16 Claims. (Cl. 112—59)

The present invention relates to improvements in shoe sewing machines and more particularly to thread tension devices employed in wax thread machines for the combined operations of sewing and lasting stitchdown shoes, as disclosed in U. S. Letters Patent to Leveque, No. 1,864,510, dated June 21, 1932.

The machine of the patent referred to is constructed and arranged to sew together in lasted relation the projecting marginal portions of the sole and upper of a stitchdown shoe and to draw the upper tightly into the angle between the side of the last on which the upper is supported and the projecting margin of the sole by the tension on the sewing thread. To produce the best results, it is desirable to impart uniformly to the sewing thread as high a degree of tension as possible without unduly straining or breaking the thread. For this reason, it has been the practice heretofore to employ the best quality of sewing thread, composed of long fiber linen, and the tension on the thread is regulated by a dry thread tension device located between the thread supply and a thread lubricating and waxing apparatus. This thread tension device comprises a pair of spring-pressed washers mounted on a supporting shaft, between which washers the thread passes. Due to the construction of the tension device, if cotton thread composed of low quality short fibers is used, the fibers will be come broken off and wedged between the disks, with the result that improper thread tension will occur and the lasting operations of the machine will be adversely affected. If this same tension device is located between the lubricating apparatus and the sewing devices so as to act directly on freshly wetted thread, the frictional engagement of the thread with the tension washers becomes erratic and uncontrollable for practical sewing operations.

The usual form of thread tension device employed with freshly waxed or lubricant wetted thread in machines for operating upon shoes is constructed with a brake retarded rotating thread engaging wheel having peripheral tabs bent alternately in opposite directions between which the thread passes. By providing a brake not engaging the thread directly and acting to wedge the thread in the crevices formed by the tabs on the wheel, more nearly uniform tensional effects may be produced than with tension washers acting directly on the thread. However, there still is a more or less uncontrollable factor contributing to the tension imparted to a wet thread passing over a tension wheel of this na-

ture. During the passage of thread along the crevices between the tabs of the wheel, the tension in the thread is built up progressively along the length engaging the wheel until it reaches the maximum imparted value. Due to the increasing tension in the thread engaging the wheel and the lubricant covered surfaces involved, the thread stretches and slips to a certain extent along the periphery of the wheel. This slipping may cause irregular action upon the tension.

In order to avoid substantial slipping of wet thread on a tension wheel, the thread is sometimes wrapped through more than one complete turn around the periphery of the wheel, the outgoing portion of thread leaving the wheel being overlapped in the crevices between the tabs of the wheel by the portion of thread first coming into engagement with the wheel. The outgoing portion of thread is pressed deeply into the crevices between the tabs on the wheel by the incoming portion of thread and in order for the thread to leave the wheel, it must raise up the overlapping incoming portion of thread from the crevices and push it to one side. While overlapping the thread about the periphery of the wheel is effective to prevent irregular tension, one objection to this method is in difficult regulation of the degree of tension imparted by the wheel where changes are necessary.

Since the tension in the thread must be maintained as high as possible in the patented machine commensurate with the strength of the thread, when thread of different sizes and qualities is employed it is necessary to vary the degree of tension through wide ranges. If the thread is wrapped entirely around the tension wheel so as to overlap itself at least along a portion of the wheel periphery, a variation in pressure of the brake on the wheel may not be sufficient to provide the necessary amount of variation in tension control for thread of different sizes and qualities.

Certain objects of the present invention are to simplify and improve the operation of a sewing machine, particularly when designed for lasting operations, as in the machine of the patent above referred to, and to render possible the use with the machine of both the highest quality long fiber linen thread and the most inexpensive short fiber cotton thread, without impairing the quality of the work performed or rendering it difficult to adjust the sewing thread tension. Other objects of the invention are to equip the sewing, lasting machine of the Leveque patent with a wet thread tension wheel located more advantageously.

ly than heretofore between the thread lubricating and waxing apparatus of the machine and the stitch forming devices and to so arrange the tension wheel that it may be adjusted accurately and easily without special skill or ability on the part of the operator.

With these and other objects in view, a feature of the present invention consists in the provision of a thread tension wheel located between the wax pot and the stitch forming devices of a shoe sewing and lasting machine and of adjustable means for rendering possible a change in length of overlap in thread which is wrapped about the periphery of the wheel to vary the degree of tension imparted by the wheel to the thread when threads of different sizes and qualities are used. In one embodiment of this feature of the invention, the tension wheel is mounted for movement relative to the adjacent thread guides, and in another embodiment of the same feature, a thread guiding pulley is mounted upon an adjustable arm movable with respect to the tension wheel. In the present form of this feature, the tension wheel is provided with a friction brake, the main driving clutch treadle for the machine being connected to a plate on a tension wheel supporting shaft, which plate has a projection cooperating with a cam on a tension shaft bearing to cause the tension brake to be applied and relieved, and means for adjustably securing the bearing in the machine frame permits the application and release of the tension brake to take place simultaneously with the clutching and unclutching action of the treadle. Other features of the invention consist in certain constructions, combinations and arrangements of parts hereinafter described and claimed, the advantages of which will be apparent to those skilled in the art from the following description.

In the accompanying drawings, Fig. 1 is a view in side elevation, looking from the left, of a shoe sewing and lasting machine, partly broken away, embodying the features of the present invention; Fig. 2 is a sectional detail view, on an enlarged scale, of the thread tension device illustrated in Fig. 1, with the parts in positions assumed during low speed sewing operations; Fig. 3 is a view in elevation, and on a somewhat enlarged scale, of the upper forward portion of the machine, with parts of the enclosing housing broken away to illustrate the stopping mechanism; Fig. 4 is a sectional detail view of the thread tension device illustrated in Fig. 2, with the parts in positions assumed with the machine stopped; Fig. 5 is a view in side elevation of the upper forward portion of the machine illustrating an alternative form of thread tension device for use with the machine of Fig. 1; and Fig. 6 is a sectional detail view, on an enlarged scale, of the thread tension device shown in Fig. 5.

The illustrated machine, so far as its stitch forming and lasting devices are concerned, is the same in construction and mode of operation as the machine disclosed in the Leveque patent above referred to. The lasting operations are performed in part by a pair of work gripping and feeding rolls 2 between which the upper and sole of a shoe are drawn into preliminary lasted relationship. In the machine of that patent, a stationary dry thread tension device is located between the thread supply consisting of a holder corresponding to the holder 3 illustrated in Fig. 1 of the present drawings, and a thread lubricating apparatus corresponding to, but not exactly of the same construction as that illustrated here-

in by the container 4. The tension device of the patent, therefore, acts on the thread while in unlubricated condition, the frictional drag being exerted directly on the thread between a pair of yieldingly pressed disks. The frictional drag on the thread imparted by the disks of the patent is substantially uniform while the thread is dry and is not detrimental to the thread when high quality long fiber linen thread is employed, but

if an attempt is made to sew on the patented machine with inexpensive grades of short fiber cotton thread, the ends of the fibers will be broken off or bent back as the thread is being drawn between the disks. As a result, the fibers tend to collect at the point of entry between the disks, either causing sudden irregular resistances to be applied or the disks to become permanently wedged apart by the accumulated broken off fiber ends.

20 The machine of this Leveque patent requires the use of a heavy tension because in the lasting operations of the machine, the tension of the thread alone brings the upper of the shoe being operated upon into final permanent lasted relationship with the sole and other parts of the shoe. If a wet thread rotating tension wheel having a friction brake of the usual form is employed, it is difficult, if not impossible without replacing parts of the machine, to adjust throughout sufficiently wide ranges the tension on threads of varying strengths and qualities which may be used because of the necessity of operating the machine with a tension close to the breaking point of the thread.

25 To overcome the disadvantages of a stationary dry thread tension and to provide a thread tension wheel having a sufficient range of adjustment to accommodate its action for use with different grades of thread from the best quality 30 long fiber linen thread to the cheapest short fiber cotton thread, the machine of the present invention is equipped with a rotating thread tension wheel 6 of well-known construction so arranged that when a thread is wrapped entirely around 35 the wheel and into overlapping relationship with itself, the length of overlap in the thread engaging the wheel may be varied to suit any type of thread. The periphery of the tension wheel 6 is provided with thread guiding tabs 8 of well-known construction bent alternately in opposite directions forming crevices within which a portion 10 of the thread moving out from between the tabs 8 towards the stitch forming devices is 40 pressed by the portion 12 of the thread first coming in contact with the wheel. By varying the length of overlap between the outgoing and incoming portions of thread 10 and 12, the pressure exerted by the incoming portion against the outgoing portion of thread may be changed by a 45 substantial amount, greater than the variation obtainable with any practical form of adjustable friction brake alone, even with small changes in the length of overlap between the thread portions. The pressure of the incoming portion of 50 thread tends to force the outgoing portion of thread into the crevices between the tabs and not only reduces slippage of the thread, but adds to the tension in the thread by an amount required to raise the incoming thread portion and force it clear of the outgoing thread portion. Also, the 55 pressure of the incoming thread portion 12 on the outgoing thread portion 10 tends to carry the outgoing thread portion with the wheel away from its natural tangential relationship with the 60 periphery of the wheel, indicated by the dot- 65

dash lines (Fig. 3), thus still further increasing the resistance to rotation of the wheel by the pull of the thread.

The tension wheel 6 is mounted for rotation upon a shouldered shaft 14 secured to an arm 16 bolted at 18 to one end of a link 20, the other end of which is slotted and clamped between parallel flanges on the lubricant container. The thread passes from the supply 3 over a pulley 22 downwardly into the wax container 4, upwardly through a thread wiper and guide 24 on the container, entirely around the periphery of the tension wheel and into overlapping relationship with itself and downwardly through a fixed thread guide 26 on the machine frame. From the guide 26, the thread passes over a plate-like member 28 secured to a reciprocating needle bar 30 acting as a take-up and downwardly to the eye of a sewing needle 32 secured in the bar 30. The pull exerted by the stitch forming devices on the thread, as a result of the movements of the stitch forming devices, is intermittent and pulsatory, tending to cause variations in amounts drawn past the tension wheel 6. This intermittent movement of threads adds still further difficulty to proper adjustment of thread tension.

To adjust the tension imparted to the thread by the stitch forming devices, a clamp screw 33 on the container 4 and the bolt 18 on the link 20 are loosened so that the tension wheel may be moved by sliding the link 20 between the flanges on the container 4 and by changing the angular relation of the arm 16 with the link 20. Loosening both the clamp screw 33 and the bolt 18 enables the position of the tension wheel to be changed vertically without any other complicated adjustments in the machine. Thus, the angle between the incoming portion of thread 12 extending towards the tension wheel from the guide 24 and the outgoing portion of thread 10 extending from the tension wheel to the guide 26 may be set and the length of overlap between the thread portions varied accordingly.

As illustrated in Fig. 3, the overlapping portions 19 and 12 of the incoming and outgoing thread engage between one-third and one-half of the periphery of the thread tension wheel. The incoming portion of thread presses the outgoing portion firmly into the crevices between the tabs on the wheel and reduces slippage of the thread on the wheel in a well-known manner. With a substantial length of overlap, as illustrated, the drag exerted by the tension wheel corresponds closely with the force required to rotate the wheel against the brake plus the force required to raise the incoming portion of thread from the crevices between the tension wheel tabs and to displace the incoming portion of thread while the outgoing portion is being drawn towards the stitch forming devices. But probably the greatest factor tending to impart tension to the thread is the result of the incoming thread portion retaining the outgoing thread portion within the crevices between the tabs on the wheel periphery beyond a tangent position with relation to the wheel. By retaining the outgoing thread portion 10 on the wheel beyond the tangent position, a far greater pull on the thread is required to rotate the wheel with the same brake pressure adjustment. With any given quality and size of thread, the degree of tension imparted by the tension wheel thus may be regulated roughly without adjusting the pressure of the tension wheel brake of substituting or replacing parts of the machine.

The tension wheel brake of the construction in Figs. 1 to 4 inclusive comprises a leather faced brake plate 34 and a leather faced washer 36 pressed against the opposite sides of the tension wheel by means of a compression spring 38 coiled around the tension wheel shaft 14 between a collar 40 on the shaft and an adjustable thumb nut 42 threaded onto the end of the shaft, the washer 36 being held from rotation with, but slideable along, the shaft 14. To release the tension wheel brake so that the thread may be drawn more freely from the tension wheel at the end of a seam, the plate 34 is rotatably mounted on the shaft 14 and provided with an arm pivotally connected to one end of an adjustable link 44, the other end of which is connected to a bell crank 46 actuated by a link 48 connected with a treadle controlled driving and stopping mechanism for the machine. The plate 34 at the side opposite from the tension wheel is formed with a projection 49 cooperating with a cam 50 on the arm 16 so arranged that when the driving and stopping mechanism brings the machine into stopping position, the force of the spring 38 will be taken up by a shoulder 51 on the tension wheel shaft 14 which engages the collar 40 (see Fig. 4).

As a simple and effective means for relieving the pressure somewhat of the brake on the tension wheel without removing the pressure entirely, the cam 50 and the projection 49 are each formed with oppositely inclined surfaces. In the position of the parts as illustrated in Fig. 4, no pressure is exerted by the brake against the tension wheel and the pressure applying surfaces of the projection 49 and the cam 50 are in contact substantially through their entire lengths. When the machine is started and the driving mechanism is initially thrown into operation, the highest parts of the pressure applying surfaces on the projection and cam only are brought into engagement, as illustrated in Fig. 2. Under this condition, a maximum tension is applied to the thread. Upon further movement of the driving and stopping mechanism, the oppositely inclined pressure relieving surfaces of the plate and cam move into contact, partly reducing the force applied to the brake by the spring 38. The effects of relieving the pressure of the spring on the tension brake is well understood and is particularly advantageous in a combined sewing and lasting machine of the type illustrated, where continual change in the speed of the machine occurs to suit the requirements of the lasting operation about the curved portions of a shoe. Where a machine is being operated at high speeds, there is less necessity for pulling the upper against the cutsole with a high degree of thread tension and when sewing about the curved parts of a shoe, where greater resistance is offered against pulling the upper into proper lasted relationship, it is natural for an operator to slow the machine down to a more moderate operating speed.

The means for regulating the speed of the machine is substantially the same as that described in the patent and consists briefly of a main driving clutch 52 (Fig. 1) acted upon to start the machine into operation by a clutch actuating finger 54 secured to a jack shaft 56 carrying an arm 58 pivotally connected to a treadle rod 60. The treadle rod 60 is in turn connected to a driving and stopping treadle 62. Downward movement of the treadle 62 causes idle movement of the clutch operating finger 54 from the full-

line position to the dot-and-dash line position of Fig. 1. During this idle movement, a rod 64 also connected to the arm 58 is moved downwardly, moving an arm 66 secured to a shaft 68 rotatable in the machine frame. Rocking the shaft 68 draws the link 48 downwardly, through connections inside the frame of the machine described in the patent referred to, by a sufficient amount to cause the thread tension to be rendered effective with a maximum pressure of tension spring 38, as indicated in Fig. 2. Thus, when the machine is started in operation, the greatest possible amount of tension is applied to the thread. Upon further downward movement of the treadle 62, the clutch 52 is actuated to start the machine slowly in operation and any further movement of the treadle beyond the slow speed starting position causes the projection 49 on the plate 34 of the tension brake to swing past the top of the cam 50 (Fig. 2) and to relieve somewhat the pressure of the brake applying spring 38. When the treadle is fully depressed to cause the machine to operate at its highest speed with the clutch fully effective, the pressure of the spring on the tension wheel brake is substantially relieved. To adjust the relationship between the projection 49 and the cam 50 to become effective at the slow speed starting position of the treadle, the link 44 is made in two parts joined together by a turn buckle 70.

As in the machine of the above identified patent, the stopping and starting mechanism of the present machine consists of a crank oscillated bell crank 72 (see Fig. 3) and a needle actuating bell crank 74 arranged to be connected together by a latch 76 pivoted on the bell crank 74 and acted upon by a pin 78 on an arm 80 secured to the shaft 68. When the shaft 68 is rocked in starting the machine in operation, the pin is moved away from the latch 76 and a spring 82 connected with the latch causes it to engage a pin on the bell crank 72. The usual arrangement of the machine of the patent is such that the latch 76 does not connect the bell cranks 72 and 74 until the clutch is rendered effective. With the use of a tension which is partly relieved when the machine is sewing at high speeds, it is desirable to so adjust the relationship between the point of engagement of the clutch during the movement of the treadle and the action of the latch that the latch may connect the bell cranks 72 and 74 before the clutch becomes effective or even partially so. By so doing, adjustment of the relationship between the projection 49 and the cam 50 for the desired application and partial relief of sewing thread tension is simplified and once the latch 76 is effective, the pin 78 on the arm merely moves away from the latch without causing further actuation thereof while the treadle is being depressed further to relieve the sewing tension.

In the form of the invention illustrated in Figs. 5 and 6, the length of overlap in thread wrapped about the periphery of the tension wheel is controlled by a movable thread guide adjustable with respect to the tension wheel to change the angle between the incoming and outgoing portions of thread. The tension wheel located at 80 is similar to the wheel 6 in the construction previously described, and is rotatably mounted on a shoudered shaft 82 which in turn is rotatably supported in a sleeve-like bearing 84 secured by a set screw 86 within a hub at the upper end of an arm 88. The arm 88 is clamped at its lower end by a bolt 90 to a bracket 92 secured to the

frame of the machine. The adjustable thread guide comprises a pulley 94 carried by one end of an arm 96, the other end of which is slotted and is received on the clamp bolt 90. Upon loosening the clamp bolt 90, the arm 96 may be swung to any of a number of positions between that indicated in the full line position of Fig. 5 to a position in which the pulley 94 assumes the dot-dash line position. By adjusting the arm 96 between these positions, the length of overlap between the incoming and outgoing threads may be regulated through a relatively wide range. Also, the tension wheel supporting arm 88 may itself be moved somewhat about the clamp bolt 90 to provide further adjustment of thread overlap. From the tension wheel, the outgoing portion of thread passes to the thread guide 98 of the same construction as the guide 26 previously referred to.

The brake for the tension wheel 80 consists of a leather faced washer 100 held from rotation on the shaft 82, but slideable lengthwise thereof, and a leather facing 102 backed by the end of the bearing 84 and the portion of the arm 88 receiving the bearing. For applying a pressure to the brake, a reduced end of the shaft 82 has coiled about it two springs, one 104 inside the other 106, wound in opposite directions to prevent escape of the inner coils through the outer coils. The outer spring 106 is substantially weaker than the inner spring 104 and is compressed between the washer 100 and a thumb nut 108 threaded on the reduced end of the shaft 82. This outer spring 106 is for the purpose of exerting a slight tension on the thread while the machine is stopped, thus preventing excessive stripping of thread from the machine by the operator. The inner spring 104 is compressed between the thumb nut 108 and a collar 110, held when the machine is stopped against a shoulder 111 on the shaft 82 and when the machine is running against the brake washer 100, depending upon the lengthwise position of the shaft.

To move the tension shaft 82 lengthwise, the unreduced end is threaded and received in the hub of an arm 112, a check nut 114 being provided to lock the shaft to the arm. One face of the hub on the arm is formed with a cam 115 cooperating with a projection 116 at one end of the sleeve bearing 84 so that when the arm 112 is rocked, the cam 115 will climb up on the projection 116, compressing the spring 106 slightly and bringing the collar 110 to bear against the washer 100. When the arm is moved in the opposite direction, the spring 106 moves the shaft to carry the shoulder 111 against the collar 110 and move the collar from engagement with the washer 100. Rocking movement is imparted to the arm 112 by an adjustable link 118 connected with an arm 120 on a short shaft 122 rotatable in the machine frame. The short shaft 122 also has secured to it an arm 124 connected by a link 126 with a valve actuating arm 128, the purpose of which is disclosed more fully in the patent to Leveque No. 1,972,023, of August 28, 1934. Intermediate the ends of the link 126 is pivotally connected a link 129 corresponding to the link 48 in the construction previously referred to. Other portions of the machine illustrated in Figs. 5 and 6, including the thread lubricating apparatus 130, are substantially the same as those disclosed in the Leveque patents.

To change the time at which the application and release of the thread tension brake, in the construction of Figs. 5 and 6, take place during

clutching and unclutching movements of the treadle 62, regardless of wear in the driving clutch or other inequalities, the set screw 86 is loosened and the bearing 84 turned to an adjusted position to bring the projection 116 into proper relation with the movements of the cam 115 on the arm 112.

While the construction illustrated in Figs. 5 and 6 is arranged to release or relieve the tension on the thread only in stopping the machine by properly shaping the cam 115 and projection 116, relief of the tension may also be made to occur when the machine is being operated at high speed. When thus arranged, the braking action produced by the spring 106 may be sufficient for high speed sewing operations and the pressures of both springs 104 and 106 for low speed sewing.

To prevent lubricant from being thrown from the thread by centrifugal force and by the rubbing action of the incoming portion of thread on the outgoing portion of thread, towards the operator of the machine and towards the position where the shoe being operated upon is held, there is mounted in front of the tension wheel 80, as illustrated in Fig. 5, a substantially vertical guard plate 131 made fast at its lower end to the machine frame and curved slightly at its upper end with a rearward sweep approximately concentric with the center about which the wheel rotates. The thread, as it leaves the plate-like take-up member 28, passes downwardly between separated flanges, one of which is indicated at 132 on the guard plate 131, which flanges are perforated to receive a securing stud 134 mounted in the machine frame. Thus, the guard plate protects the operator from lubricant thrown off by the thread while passing over the tension wheel and guides, leaving the thread uncovered only along the straight portion extending downwardly between the flanges on the guard plate towards the stitch forming devices.

The nature and scope of the invention having been indicated, and a construction embodying the several features of the invention having been specifically described, what is claimed is:

1. A shoe sewing and lasting machine in which the tension on the thread assists in the lasting operations having, in combination, stitch forming devices including a needle, a wax pot, a thread tension wheel disposed between the wax pot and the stitch forming devices, an adjustable friction brake acting on the tension wheel, thread guides for directing the thread into overlapping relation along a substantial portion of the wheel periphery when wrapped entirely around the wheel, and means for supporting the tension wheel for rotation arranged for movement relative to the thread guides to enable the degree of tension imparted by the wheel to the thread to be adjusted throughout a range substantially greater than that obtainable by adjustment of the friction brake alone.

2. A shoe sewing and lasting machine in which the tension on the thread assists in the lasting operations having, in combination, stitch forming devices including a needle, a wax pot, a thread tension wheel disposed between the wax pot and the stitch forming devices, and means for directing the thread towards and from the tension wheel comprising an adjustable guide for changing the angle between the portions of thread extending towards and from the wheel to vary the degree of tension imparted by the

wheel to the thread when the thread is wrapped in overlapping relation about the wheel.

3. A shoe sewing and lasting machine in which the tension on the thread assists in the lasting operations having, in combination, stitch forming devices including a needle, a wax pot, a thread tension wheel disposed between the wax pot and the stitch forming devices, thread guides including a thread guiding pulley adjacent the tension wheel for directing the thread into overlapping relation along a substantial portion of the wheel periphery when wrapped entirely around the wheel, and an adjustable pulley supporting arm movable with respect to the tension wheel to change lengths of overlapping thread.

4. A shoe sewing and lasting machine in which the tension on the thread assists in the lasting operations having, in combination, stitch forming devices including a needle, a wax pot, a thread tension wheel having oppositely bent tabs extending from its periphery and between which tabs the thread is supported, means for directing the thread towards and from the tension wheel with the thread wrapped entirely around the wheel and overlapping itself at least along a substantial portion of the wheel periphery, the outgoing portion of thread being covered by the incoming portion of thread to press the outgoing portion into the crevices between the tabs of the wheel, and means for varying the angular relation of the single thread portions extending towards and from the wheel to vary the degree of tension imparted to the thread.

5. A shoe sewing machine having, in combination, a frame, stitch forming devices in the frame including a needle, a thread tension wheel, a friction brake for the tension wheel, a shaft on which the wheel is rotatably mounted, a bearing for the shaft on the frame, an arm on the shaft having a cam cooperating with a projection on the bearing to cause the brake to be applied and relieved, a main driving clutch for the machine, a treadle for actuating the clutch and arm, and means for adjustably securing the bearing on the frame to change the time at which the application and release of the tension brake takes place during the clutching and unclutching movements of the treadle.

6. A shoe sewing machine having, in combination, a frame, stitch forming devices in the frame including a needle, a thread tension wheel, a friction brake for the tension wheel, a shaft on which the wheel is rotatably mounted, a bearing for the shaft on the frame, an arm on the shaft having a cam cooperating with a projection on the bearing to cause the brake to be applied and relieved, a main driving clutch for the machine, a treadle for actuating the clutch and arm, and a set screw for clamping the bearing on the frame arranged to release the bearing for rotation to a position in which the movements required of the arm while applying or releasing the brake take place during clutching and unclutching movements of the treadle.

7. A shoe sewing machine having, in combination, a frame, stitch forming devices in the frame including a needle, a thread tension wheel, a shouldered shaft on which the wheel is rotatably mounted, an arm on the shaft, a bearing for the shaft on the frame, cam and projection means on the arm and bearing, respectively, to move the shaft lengthwise when the arm is actuated, a friction brake on the shaft for the tension wheel, a first spring on the shaft acting continuously between the end of the shaft and

the brake to restrain rotation of the tension wheel, and a second spring on the shaft arranged to be compressed by the shoulder when the arm is moved in one direction and to expand against the brake when the arm is moved in the other direction.

8. A shoe sewing machine having, in combination, a frame, stitch forming devices in the frame including a needle, a thread tension wheel, a shouldered shaft on which the wheel is rotatably mounted, an arm on the shaft, a bearing for the shaft on the frame, cam and projection means on the arm and bearing, respectively, to move the shaft lengthwise when the arm is actuated, a friction brake on the shaft for the tension wheel, a first spring on the shaft acting continuously between the end of the shaft and the brake to restrain rotation of the tension wheel, a collar on the shaft, and a second spring on the shaft between the collar and said end of the shaft arranged to be compressed by the collar when the shoulder on the shaft is moved by the arm against the collar and to expand against the brake when the shoulder is moved in the other direction.

9. A shoe sewing machine having, in combination, a frame, stitch forming devices in the frame including a needle, a thread tension wheel, a friction brake for the tension wheel, a shaft on which the wheel is rotatably mounted, a bearing for the shaft on the frame, an arm on the shaft having a cam cooperating with a projection on the bearing to cause the brake to be applied and relieved, a main driving clutch for the machine, a treadle for actuating the clutch and arm, a first coil spring on the shaft for pressing the brake, a second coil spring on the shaft for pressing the brake, means for relieving the brake from the pressure of the first spring while the second spring still remains effective, and a thumb nut on the shaft for adjusting the pressures of both springs simultaneously.

10. A shoe sewing machine having, in combination, a frame, stitch forming devices in the frame including a needle, a thread tension wheel, a friction brake for the tension wheel, a shouldered shaft on which the wheel is rotatably mounted, a first coil spring on the shaft for pressing the brake, a collar on the shaft inside the first coil spring, a second coil spring on the shaft acting to press the collar against the brake, and means for moving the shaft lengthwise to cause the pressure of the second spring to be transferred from the brake to the shoulder on the shaft.

11. A shoe sewing and lasting machine in which the tension on the thread assists in the lasting operations having, in combination, stitch forming devices including a needle, a sewing shaft, mechanism connecting the sewing shaft with the needle comprising an element movable to disconnect the needle from the shaft, treadle controlled means for actuating said element, a sewing thread tension device, and means connected with the treadle controlled means for rendering the tension effective and thereafter for decreasing the effect of the tension device on the thread upon continued movement of the treadle controlled means from needle disconnecting position beyond a position where the needle is connected with the sewing shaft.

12. A shoe sewing and lasting machine in which the tension on the thread assists in the lasting operations having, in combination, stitch forming devices including a needle, a sewing shaft, mechanism connecting the sewing shaft with the needle comprising an element movable to disconnect the needle from the shaft, a driving clutch for the sewing shaft, treadle controlled means for actuating the clutch to drive the sewing shaft and said element to connect the needle, a sewing thread tension device, and connections between the treadle controlled means and the tension device for rendering the tension device effective and for decreasing the tension on the thread when the treadle controlled means is moved in a direction to cause the clutch to drive the sewing shaft beyond the position where the needle is connected with the sewing shaft.

13. A shoe sewing and lasting machine in which the tension on the thread assists in the lasting operations having, in combination, stitch forming devices including a needle, a sewing shaft, mechanism connecting the sewing shaft with the needle comprising an element movable to disconnect the needle from the shaft, a driving clutch for the sewing shaft, treadle controlled means for actuating the clutch to drive the sewing shaft and said element to connect the needle, a sewing thread tension wheel, a brake for the wheel, a cam for actuating the brake, and connections between the cam and treadle controlled means for releasing the wheel from the brake when the needle is disconnected from the sewing shaft and for relieving the effect at least in part of the brake on the tension wheel during sewing when the treadle controlled means is moved in a direction to cause the clutch to drive the sewing shaft beyond a position where the needle is connected with the sewing shaft.

14. A shoe sewing and lasting machine in which the tension on the thread assists in the lasting operations having, in combination, stitch forming devices including a needle, treadle controlled means for causing the stitch forming devices to be actuated, a thread tension wheel, a shaft on which the tension wheel is rotatably mounted, a brake for the tension wheel, a spring for rendering the brake effective, and means for releasing the brake from the pressure of the spring comprising a cam connected to the treadle controlled means having oppositely inclined surfaces, one of which is active to apply the pressure of the spring to the brake when the machine is being started in operation and the other of which is active to relieve in part the pressure of the spring on the brake when the machine is being operated at maximum speed.

15. A shoe sewing and lasting machine in which the tension on the thread assists in the lasting operation having, in combination, stitch forming devices including a needle, treadle controlled means for causing the stitch forming devices to be actuated, a thread tension wheel, a shaft on which the tension wheel is rotatably mounted, a brake for the tension wheel, a spring for rendering the brake effective, and means for releasing the brake from the pressure of the spring comprising a cam connected to the treadle controlled means having oppositely inclined surfaces, one of which is active to release wholly the pressure of the spring on the brake when the machine is stopped and the other of which is active to relieve in part the pressure of the spring on the brake when the machine is being operated at maximum speed.

16. A shoe sewing machine having, in combination, a frame, stitch forming devices in the frame including a needle, a thread tension wheel, thread guides for changing the course of the thread and directing it towards and from the tension wheel

and in a substantially straight path towards the needle, thread lubricating apparatus through which the thread passes before engaging the guides and tension wheel, and a guard for shielding the operator from lubricant thrown off by the thread as it passes over the guides and tension wheel comprising a plate extending in proximity

to the guides and tension wheel and having side flanges attached to the machine frame, between which flanges the substantially straight path of thread passes.
